B. SCHAEFER, JR

SMOKER'S STAND

Filed March 9, 1925

INVENTOR:
Bernhard Schaefer Jr.,
BY
John Elias Jones,
ATTORNEY.

Patented July 7, 1925.

UNITED STATES PATENT OFFICE.

BERNHARD SCHAEFER, JR., OF CINCINNATI, OHIO.

SMOKER'S STAND.

Application filed March 9, 1925. Serial No. 14,302.

To all whom it may concern:

Be it known that I, BERNHARD SCHAEFER, Jr., a citizen of the United States of America, and a resident of Cincinnati, in the county of Hamilton and State of Ohio, have invented a certain new and useful Improvement in Smokers' Stands, of which the following is a specification.

This invention relates to the convenient article of companion-service furniture used mainly by tobacco smokers and commonly known as smokers' stands that are ordinarily composed of usually light pedestals surmounted by receptacles for the ashes, partly used cigars and used matches, as well as supporting arms or holders for the temporary resting of the cigars and unused matches, and the object of the invention herein is to provide a removable ash tray or cup in the bottom of the said receptacle whereby the contents of the tray can be easily handled and emptied without disturbing or handling the stand itself nor any other part thereof, or thing thereon.

The details of structure of the improved stand will be fully hereinafter described in connection with the accompanying sheet of drawings, in which—

Figure 1 is a perspective view of the improved smoker's companion-service stand embodying my invention; Figure 2, a perspective view showing the said removable ash-tray taken apart from the stand; and Figure 3, a vertical section of the upper part of the stand, taken on the dotted line 3, 3, of Figure 1, to show most clearly the said removable ash-tray improvement herein.

4 indicates the upright rod or tubing forming, with its base 5, the supporting pedestal of the stand.

6 indicates (as a whole) the main receptacle surmounting the upper end of the said pedestal rod or tubing 4 and composed of a bowl 7 having a flanged rim 8 and an open or grated extension-bottom, all preferably made or cast integral. The extension-bottom is a somewhat deep one and has at the lower ends of its vertical spider-arms 9 a horizontal hub or centrally-orifized boss 10 that is internally threaded for the engagement of the threaded upper end of the said rod or tubing 4, as best shown in the section, Fig. 3. The upper end or edge of the said grated or barred extension-bottom is shouldered at 11 and an open, easily

cleansable well or chamber is thus provided by said extension-bottom for a removable cup or tray 12 whose upper edge or rim is laterally extended or flanged at 13 for seating or resting on the said shoulder 11 in the centrally-orifized bottom of the said bowl or main receptacle 7. The cup 12 is made of metal, pottery-ware, or any other suitable material adapted to its purpose 65 herein.

An arched cross-wire 14 is anchored at its opposite ends in the upper edge of the said removable cup or tray 12 for use in facilitating the handling of the cup to and 70 from place in the said bowl or receptacle 7 and, also, for very convenient and effective use in stripping ashes from the cigars of the smokers that have the stand in handy position alongside them when in use. 75

Concave, radial rests 15 are provided along the flanged rim 8 of the bowl 7, for supporting the cigars while in use and with their lit ends disposed inwardly, for the proper dropping of the ashes into the bowl. 80 An upright match-box holder 16 is also provided on the said flanged rim 8, the same as in many of the smokers' stands in general use.

The removable ash-tray is preferably a 85 somewhat deep one, for accommodating a quantity of ashes and other refuse dropped into the bowl and thereby further avoid the heaping up of the said refuse in the bowl.

The ash-tray can be easily removed from 90 place, whenever desired, to empty its contents, and without lifting or otherwise disturbing the stand itself that heretofore had to be raised and then turned upside down, or tilted sidewise, to empty the contents of 95 the bowl that also disturbed the cigars and the matches on the rim of the bowl and, therefore, was very inconvenient and undesirable.

My device, taken as a whole, is preferably 100 a knockdown one that has its main upright rod 4 provided with a screw-threaded connection at its opposite ends with the bowl drop-extension and the base 5, whereby it can be easily and cheaply made and then 105 compactly packed for stock, boxing, handling and shipping.

I claim:—

1. As an article of manufacture, a smok- 110 er's stand comprising a pedestal, a bowl or main receptacle surmounting said pedestal and having a centrally-orifized bottom, and

a removable cup or tray seating in the said orificed bottom of the bowl and adapted to contain ashes and other refuse dropped in the bowl.

- 5 2. As an article of manufacture, a smoker's stand comprising a pedestal, a main receptacle or bowl surmounting said pedestal, a shouldered central orifice in the bottom of the said bowl, a deep tray or cup provided with a handle and having a flanged or extended rim adapted to engage the said

shouldered central orifice in the said bowl for removable support, and an open, drop or pendent extension-bottom provided on the bowl for accommodating the said tray 15 or cup in removable position or place for the reception and easy discharge of the ashes and other refuse therefrom without moving or disturbing the stand itself, substantially as shown and described.

BERNHARD SCHAEFER, JR.
